Specification of Letters Patent.

Patented Apr. 3, 1917.

Application filed July 8, 1912, Serial No. 708,108. Renewed October 10, 1914. Serial No. 866,056.

To all whom it may concern:

Be it known that I, ERNEST DUSCHER, a citizen of the United States, residing at La Crosse, in the county of La Crosse and State of Wisconsin, have invented a new and useful Improvement in Printing-Machines, of which the following is a specification.

My invention relates to improvements in printing machines and its object is to provide improved means whereby letters having different names and post offices of addressees and envelopes having addresses corresponding with said names and post offices in the letters may be printed successively. In carrying this invention into use a type bed is employed which may be introduced on the main type bed of a printing machine in connection with the type form thereon to carry a supplementary form exchangeable and adjustable with relation to the other forms carried by the machine. In connection with this object my invention is adapted to the insertion and removal of supplementary type forms such as are used in printing different names and post offices of addressees on copied letters, to the printing of said names and post offices on envelopes and to the positioning of the paper and envelopes in the machine over the type form so as to register letters or envelopes accurately over the type form and portions thereof.

This invention is simple in construction and effective in operation, the particular adaptability of the construction illustrated being especially appropriate but not necessarily confined to use in connection with the apparatus described in my companion application Serial No. 660,425 filed on November 15, 1911, for filling in attachment for printing machines.

In the drawings with which I have illustrated my invention and which form part of this specification, Figure 1 is a plan view of a printing machine of the class mentioned equipped with my improvement; Fig. 2 is a sectional view on the line X—X, Fig. 1 showing a side elevation of my improvement; Fig. 3 is an enlarged sectional view of a detail showing a portion of the type bed and of the form thereon also a portion of the ribbon and of the parts which are employed for positioning envelopes over the type form; Fig. 4 is a side elevation of a detail, portions thereof being broken away showing an envelop lifter and spacer; Fig.

5 is a perspective of a detail portion of the envelop lifter and spacer. Fig. 6 is a side elevation of the envelop guide which assists in positioning the envelop laterally on the filling in block; Fig. 7 is a plan of one of the impression rollers; Fig. 8 is a plan of the filling in type block; Fig. 9 is a sectional side elevation of the construction illustrated in Fig. 8; Fig. 10 is an enlarged detail of a portion of Fig. 9 in a different position of the parts; Fig. 11 is a perspective of the supplementary type holder or name plate; Fig. 12 is a perspective of a detail showing means whereby a separate adjustment of each platen roller is provided, the carrier chain being broken away and the two platen rollers shown close together for the purpose of illustration; Fig. 13 is a perspective of an alternative form of the envelop lifter and spacer; Fig. 14 is a perspective of a detail of a portion of the construction illustrated in Fig. 13; Fig. 15 is an enlarged sectional view of a detail of the bed of the machine showing the skid rails illustrated in Fig. 12 and the envelop lifter and spacer illustrated in Fig. 13 applied thereto in connection with the type form and type block; Fig. 16 is a side view of one of the skid rails illustrated in Fig. 12, and Fig. 17 is a longitudinal section through the machine showing the construction of envelop lifter and spacer illustrated in Fig. 13 applied thereto.

In the above drawings I have shown a printing machine having a frame A, a type bed B carried by said frame, on which a form C may be supported and with which a platen D coöperates in making a printing impression. E indicates a supplementary type bed or type block which is shown mounted on the main type bed B in the main form C and carries a supplementary type holder or name plate F which is adapted to be so positioned on the type block E as to coöperate with the platen D in the same manner as the main form C on the type bed.

On the frame A are mounted sprocket wheels 2 carrying sprocket chains 3 at each side of the machine, on which is mounted a platen D in the form of a roller having a body 4 which traverses the type form and a wear wheel 5 at each end through which printing pressure is imparted to the platen. The type bed B is so positioned with relation to the path of the platen D carried by

the sprocket chains 3 that normally it travels orbitally about the type bed and above the surface of the type in the form and out of contact with it.

Printing pressure on the platen is secured by means of bars 6 at each side of the machine under pressure from the springs 7 which may be adjusted to different degrees of pressure. The under surface of each of the pressure bars 6 is formed with notches 8 bearing upon the periphery of the wear wheels 5 and producing intermittent and repeated impacts on the platen and thereby on the type in the form.

15 A skid bar 9 is shown at each side of the machine on which travels the wear wheels 5. The skid bars are mounted upon supporting pins 10 (see Fig. 3) which play loosely through the bed of the machine and upon which springs 11 are mounted between the rails and the bed, the tendency of these springs being to raise the bars. Stop nuts 12 on the lower ends of the pins limit the upward movement of the bars, the tension 25 of the springs 11 being such that normally when the platen roller is not pressed into coöperation with the type on the form in the machine by the pressure bars the skid bars support the platen roller so that it will ride above and out of coöperation with the type in the form.

30 A color inking ribbon 13 is carried in the machine between the path of the platen and the type form and is passed over suitable spools 14 connected by gears 15 with the sprockets 2. Idle rollers 16 are also journaled in the frame of the machine over which the ribbon travels in its path around the type form and onto the spools. The ribbon is adapted to be stepped forward after 35 each stroke of the platens in the usual manner by any suitable mechanism of ordinary construction. An operating handle 17 connected with one pair of sprockets 2 operates 40 the belts 3, platen D and ribbon 13.

45 My supplementary type bed or printing block E consists of a body part 18 of comparatively narrow width and extending transversely across the type bed and parallel 50 with the line of orbital motion of the platen D. The body 18 rests horizontally on the type bed B on which it is adjustable vertically by means of set screws 19, this adjustment being permanent when once made to bring the raised portion 20 of the type block to such an elevation that standard type 21 in the supplementary type form F have an 55 equal elevation with the type commonly used in the form C on the bed B.

60 The raised portion 20 which receives and supports the type of the filling in type forms extends less than the width of the type bed B, and at either end of the face 20, the body 18 is cut away or depressed in elevation so 65 that the type in the form F when resting on

or above these parts of the body 18 do not have printing contact with the ribbon 13 during the passage of the platen D. The lateral sides of the body 18 are formed with grooves 22 extending the full length thereof 70 for the engagement of the name plate F which is formed with lugs 23 adapted to travel in the grooves 22 during the longitudinal movement of the plate F along the printing block. The lugs 23 extend down 75 the sides of the printing block and into the grooves 22 and allow the type 21 carried by the name plate to rest upon the raised portion 20 when the name plate reaches that part of the block.

80 A spring 25 on the side of the printing block serves to hold the address plate in printing position on the raised portion 20 of the block, the movement of the plate being at all times controlled by the operator 85 who is able to move the plates in series into printing position by hand as fast as they are required during the operation of the machine. The extension 27 having the same width as the block E permits the name 90 plates to be pushed from the block and from under the color ribbon 13. The movement of the plates F along the block is accomplished by means of the pusher 28 which slides in a slot 29 in the block on the rod 30. 95 This rod 30 is mounted on the block and carries a spiral compression spring 31 in front of the pusher 28 said spring being compressed by the pusher during the forward movement thereof in advancing the 100 plates. Upon releasing the pusher the spring 31 returns it sharply and automatically to its original position. In order to secure the engagement of the name plate F by the pusher a spring stop 32 is mounted in the 105 pusher. This stop is adapted to recede out of the path of the paper upon the form when the pusher is released and its construction and operation are fully set forth in my companion application above referred to.

110 To prevent the interference of the plates F and the ribbon 13 during their advancement along the block E the ribbon is automatically held out of contact with the plate by means of a spring 35 positioned longitudinally of the block E and near the side of the ribbon adjacent to the approach of the block. This spring stands above the level of the type in the plate and normally keeps the ribbon raised therefrom. It is 115 however a comparatively weak spring permitting the platen to spring the ribbon into contact with the type without resistance and is formed of smooth wire to permit the unobstructed travel of the ribbon.

120 The name plate or supplementary type form F has the form of a plate with a series of slots 36 in which are mounted suitable double shoulder type 21 adapted to engage 125 the sides of the slots for support to prevent 130

lateral movement of the type when in printing position and to hold the type assembled when not being used in the machine. The type are placed in the slots in suitable form for printing the names and post offices of addressees, salutations, and the like and are locked in the slots as by compressing the shoulders of the type at the end of the series.

- 10 In addition to the platen roller D having a body the length of which extends over the entire type form including the changeable type carried by the insert or name plate, a supplemental platen D' is used which is of similar construction to the platen D excepting that its impression surface is limited in length so as to traverse over only the type carried by the filling in type holder or name plate composing the name and address of the addressee. The supplemental platen roller is carried by the chains or belts 3 and is evenly spaced from the platen element D on the belts so that the impressions made by the rollers D and D' are at even intervals.
  - 25 In Fig. 12 the platens are shown close together only for illustrative purposes.

A system of paper guides is employed for assisting in positioning sheets of paper over the entire type form including the name and post office of the addressee, and envelopes or sheets of printing material over said name and post office only or that portion thereof which may be used for addressing purposes. This system is so constructed that the sheets or envelopes are raised automatically to assist the removal of the printed material from the machine. The sheets of printing material which receive an impression from the entire type form including the names and post offices of the addressees are positioned by means of the side guides G and the longitudinal guide H, while the printing material such as envelopes which receives only the name and address of an addressee from the type in the name plate is positioned by the side guide I and the longitudinal guide J.

The guides G each of which is in the form of clips or jaws 37 rest with their lower arms 38 upon the ribbon above the type form and are adjustable longitudinally and transversely so that they may be placed in suitable position above the type form to position sheets of printing material accurately upon the ribbon above the form. The jaws 37 of the paper guides G are received together in the socket member 39 upon an arm 40 to which the jaws are secured in longitudinally adjusted position by means of a clamp 41. The arm 40 is formed on the side of the body piece 42 which is secured in transversely adjusted position upon a vertically reciprocable member 43 by means of a set bolt 44. Normally the paper guides G rest closely above the ribbon on the forward end of the form out of the path of paper strip-

pers K which are carried by the belts 3 and engage the printed material after each operation of printing in the machine and eject the material on the type form from the rear end of the machine toward which the rollers D and D' travel. In order that the paper strippers K following the platen roller D may engage the forward edge of each sheet of printing material on the form, the paper guides G are reciprocated by the member 43 so as to automatically manipulate the sheet of printed material with its forward edge in raised position to be engaged by the strippers K. The member 43 has its ends 45 slidably mounted to move vertically in the bed of the machine and is lifted by means of lever arms 46 and connecting links 47, the former being fixed upon a shaft 48 which is journaled in the frame. The shaft 48 is rocked to tilt the levers 46 by means of a crank arm 49 and push rod 50. This push rod is actuated by means of a cam 51 carried by a large gear 52 journaled on the frame and driven by a pinion 53 which is mounted upon one of the shafts 54 carrying a pair of the sprockets 2.

The longitudinal paper guide H is in the form of a vertical plate resting by gravity upon the ribbon above the form and pivotally mounted at one end upon a sliding support 55 which is adapted to be secured in laterally adjusted position by means of a thumb screw 56 upon a transverse shaft 57, said shaft being mounted above the path of the platen elements on the frame. As the platen elements travel orbitally about the type form on the bed, the paper guide H is lifted by the platen elements out of their path of travel and drops by gravity in position upon the ribbon above the type form to act as a guide for one end of the sheet of printing material which is placed above the form to be printed and against the paper guides G.

The paper guides employed for positioning the envelopes or the printing material which is to receive only the names and post offices of addressees from the filling in plates consist of members I and J. The guide I is in the form of a clip slanting upwardly which can be secured in longitudinally selected position upon the spring strip 58 by means of a screw 59 engaging in any one of the threaded openings 60 in the strip (see Fig. 5). The strip 58 is made of spring metal or other suitable material and one of its ends is hinged at 61 upon the end of the bar or block 62, the opposite end of the strip resting upon the bar and being held under tension or restrained by means of a tie bolt 63 passing freely through a horizontal web 64 formed across a recess 65 in the bar. The tie bolt 63 acts as a guide for the strip and carries an expansion spring 66 which augments the strength of the elasticity in the 130

strip. The strip rests normally a short distance above the bar leaving a space through which the inking ribbon is free to feed over the type in the form and the filling in plates when the machine is in operation. The bar 62 is adapted to be locked in the form with the filling in block E upon the bed of the machine, the bar lying parallel to the filling in block and being disposed with the hinged 5 end of the strip 58 near the forward end of the bed so that the platen element D passing upon the form will gradually impinge upon the strip 58 and press it down. As the platen element D leaves the form and the 10 filling in plate of type, the strip 58 springs back into raised position releasing the ribbon. As the platen element D' passes on to the form it rolls upon the strip 58 depressing it until the envelop is printed whereupon the strip is released and the envelop 15 raised by the strip into position to be engaged by the strippers K which remove the envelop from the machine. It will be noted that the surface of the roller D' is of sufficient length to coöperate with the type on the filling in plate and with the strip as 20 above described.

The paper guide J which serves to assist in positioning the envelops in laterally selected position upon the type form consists of a plate 67 which is selectively positioned longitudinally upon the arm 68 of the crank 69 by a thumb screw 70. The crank 69 is adapted to be secured in longitudinally adjusted position upon a clip 71 by means of a screw 72, said clip 71 being suitably placed upon one of the pressure bars 6 by means of the thumb screw 74. By turning the crank 69 in the clip 71 and setting the screw 72, the plate 67 can be regulated in height above the type form out of the path of the impression elements and by adjusting the crank 69 longitudinally in the clip 71 and the plate 67 upon the arm 68, the 25 plate can be regulated in position transversely above the type form. In positioning an envelop in the machine above the ribbon it is placed face downward with its forward extending end against the clip I 30 and with one of its edges against the plate 67. The surface of the platen element D' then engages the extending end of the envelop in the clip I and rolls over the envelop thus making a printing impression.

55 A set of paper strippers K mounted upon a shaft 73 which is carried by the belts 3 at a suitable distance from each platen element is adapted to perform the function of removing the paper and the envelops as 60 they are printed from the machine. The strippers K consisting of clips or jaws are adapted to engage the raised forward edges of the sheets and envelops immediately after they have been printed. The strippers on 65 the shaft 73 following the platen element

D are positioned transversely so as to engage the sheet of paper evenly which has been printed so that it is projected from the machine in regular order. The strippers mounted upon the shaft which follows 70 after the platen element D' are also positioned so as to perform the same function regarding the envelops.

In operation a sheet of paper of sufficient size to receive an impression from the body 75 of the form including the name and post office of an addressee and salutation, is placed in the machine and printed, it receiving an impression by the platen element D. The strippers remove the sheet of paper 80 which has been printed and an envelop is then placed, face downward, over the filling in portion of the type and adjusted to the guides I and J. It in turn receives an impression from the platen element D' and 85 the strippers remove the envelop. The machine is then in readiness to repeat the operation, a new addressing plate being placed in the machine on the filling in block before another sheet of paper and an envelop are 90 printed. It will be noted that a filling in plate is placed in the machine on the block after every two impressions are made by the plate rollers also that only the type in the main form and in the plate resting upon 95 the raised portion 18 of the filling in block is adapted to deliver a printing impression, the type in plates on the lower surfaces of the type block resting below the plane of the remaining type in the form.

100 At the delivery end of the machine are placed paper delivery slides 76 secured to the frame and upon the bar 62 is secured another paper delivery slide 77, the latter assisting in directing the envelops from the 105 machine.

The bar 62 may be adjusted in height upon the bed by screws 78 and the ribbon lifting spring 85 may be employed on the filling in block to produce unobstructed adjustment of the plates on said block and to 110 keep the ribbon when feeding out of contact with the type.

115 As illustrated in Figs. 1, 2 and 7 the wear wheels 5 are adapted to travel upon the surfaces of the single pair of skid bars 9, one bar being placed at each side of the type form on the surface of the bed while in Fig. 12 two skid bars are illustrated on each side of the bed, one for each platen 120 roller whereby the platen rollers may be adjusted to travel with their impression surfaces in the plane of the type in the form and holder. In Fig. 12 the platen rollers are shown close together, the carrier shown 125 being broken away for illustrative purposes only.

The bar 9 on which roller D travels is similar in construction to the bar 79 on which roller D' runs except that bar 9 has 130

a tabulating ribbon or strip 80 secured to its surface such as by screws 81. These bars are secured in parallel position longitudinal to the travel of the rollers D and D' on 5 each side of the form on the surface of the bed B with their supporting pins 10 playing freely through openings 82 in the bed. Each bar has a pair of vertically disposed screws 83 projecting downwardly there- 10 through by which the bars may be adjusted in height with their impression surfaces to the planes of the type in the type form and in the holder on the raised surface 20 of the type block. Perforations 84 in the 15 ribbon provide access to the adjusting screws 83 in the bar 9 for turning them. The wear wheel 5 on roller D is formed with an annular space 85 over each bar 79 while roller D' has its wheel 5 of less diameter over bar 9 than the portion thereof over 79, thus leaving a pair of skid bars 20 coacting with each impression roller to regulate its plane of travel over the type form.

In Figs. 13, 14 and 17 a modification of 25 the construction described for positioning the envelopes or the printing material which receives the address portion from the filling in plates is shown. The guide J in this construction for lateral positioning remains 30 the same as described. The guide for positioning the envelopes longitudinally over the type holder in printing position consists of a bar 86 and a strip 87 carrying the clip or stop 88, said bar being raised automatically 35 after each printing operation by the vertically reciprocable member 43. The bar 86 is adapted to be clamped longitudinally in the type form alongside of the type block E and is formed with a downwardly slanting 40 hollow rearward end having inturned upper edges 89 below which a shouldered end 90 of a strip 87 extending longitudinally on the bar 86 engages. The clip 88 can be secured to the strip 87 in longitudinally selected position by screws 91 engaged 45 in any of the sets of threaded openings 92 in the strip. The strip conforms in angular shape to the surface and end of the bar 86 so that by moving the strip with its shoulders formed by notches 93 against the in-turned edges 89 the strip is raised slightly 50 above the surface of the bar leaving a space 94 through which the ribbon 13 is free to move and feed when the platen rollers do 55 not coöperate with the type on the bed. The forward end of strip 87 is secured adjustably to an arm 95 carried by member 43 by a bracket 96 on strip 87 and an adjusting screw and nut 97 and 98. By tightening the 60 nut 98 the strip is moved longitudinally and raised by its shouldered end being moved up the inclined end of the bar 86 and by loosening the nut the operation is reversed and the space 94 diminished.

65 As the rocker arm 46 is swung up and

down automatically during the operation of the machine the member 43 is reciprocated vertically after each printing impression is made. The strip is also raised by member 43 lifting with it the envelop which has been 70 printed so that the paper strippers will engage the forward edge of the envelop and remove the envelop from the machine. The guide pin 99 on the arm 95 passes through bracket 96 and assists in preventing side 75 motion of the strip when raised. The bar 86 may be adjusted in height on the bed of the machine by screws 100 threaded downwardly through the bar.

In accordance with the patent statutes I 80 have described the principles of operation of my invention together with the apparatus which I now consider to represent the best embodiment thereof but I desire to have it understood that the construction 85 shown is only illustrative and that the invention can be carried out by other means and applied to uses other than those above set forth within the scope of the following claims.

Having described my invention, what I claim as new and desire to protect by Letters Patent is:—

1. In a printing machine, a type form having a changeable portion, a flat bed on which said form is mounted, two platen rollers adapted to coöperate with type in said form to produce printing impressions from the entire form of type and from the changeable portion successively, a carrier 95 adapted to move said platen elements orbitally over said type form, a plurality of skid rails mounted upon said bed and with which each of said platen rollers is adapted to coöperate and means for adjusting the 100 height of each of said rails to independently vary the height of travel of said platen rollers coöperating with the type in said form, whereby an even printing impression is produced by all of the type in said form or 105 said changeable portion and said rollers.

2. In a printing machine, a type form, a type block insertible in said form having longitudinal grooves in its sides, a filling in type holder having a plate slotted to receive type into engagement therewith and formed with inturned side edges adapted to slidingly engage said block in said grooves, a plurality of platen elements movable over said form and adapted to coöperate successively with type in the entire form and with type carried by said holder only and means for adjusting said platen elements evenly in height over the type in said form and carried by said holder.

3. A printing machine, comprising, in combination, a type bed, an inking ribbon above said bed, a platen adapted to coöperate with the type on said bed and said ribbon to print, a filling in holder for type hori- 130

zontally movable above said bed, a filling in type block to receive said holder, said block having a raised portion adapted to co-act with type of said holder to support them in printing position, the lower portion of said block permitting said holder to rest in non-printing position when off of said raised portion of said block, means for feeding said holder into printing position on said block and ejecting it therefrom, means for positioning sheets of printing material to print from the main body of type on said bed and means for positioning printing material over the filling in type holder on the raised portion of said block to print only from the type in said holder.

4. In a printing machine, three coöperating impression elements, one a stationary type form and the other two platen rollers arranged in series, a filling in type block placed in said form, a filling in type holder adapted to be removably placed on said block to print a name and post office of an addressee, means for feeding said holder into printing position on said block, and means for positioning printing material over the filling in type holder in printing position on said type block to print only from the type in said holder, one of said rollers coöoperating with all of the type in said form and holder and the other only with type in said holder, to print.

5. In a printing machine, three coöperating impression elements comprising, two platen rollers carried in series, a type form containing a filling in type block, a filling in type holder adapted to be removably placed on said block to print the name and post office of an addressee, means for positioning sheets of printing material over said form to print from all of the type in said form and means for positioning envelops over said filling in type holder to print only from type in said holder, said rollers being adapted to follow each other and one having its surface coöoperating with all of the type in said form and the surface of the other limited to coöperate only with type in said holder on said block.

50 6. In a printing machine, three coöperating impression elements, one a stationary type form and the other two platen rollers adapted to travel in series over said form, a filling in type block placed in said form, a filling in type holder adapted to be placed on said block to print the name and post office of an addressee, means for positioning sheets of printing material over said form to print from type in the main body and on said block and means for positioning envelops over said type on said block to print from type composing only the name and post office of an addressee, one of said rollers being adapted to coöperate with the type 65 composing the main body and filling in type

holder and the other roller adapted to co-operate only with the type in said filling in type holder.

7. A printing machine having a main type bed adapted to hold a type form, a supplemental type bed longitudinally disposed on said main bed, a type holder movable upon said supplemental bed and across said form, a push piece adapted to engage and place said holder in said form, a platen adapted 70 to coöperate with type in said main form and in the holder on said supplemental bed, a second platen adapted to coöperate only with type in said holder, means for positioning a sheet of printing material on the type 75 in said form and holder and means for positioning an envelop over the type in said holder, whereby printing may be produced successively from the main and inserted portions of type together and from the inserted portion alone.

8. In a printing machine, three coöperating elements, one a type form and the other two platen rollers movable successively over said form, a filling in type block placed in 80 said form, a type holder adapted to be placed in printing position on said block to print the name and post office of an addressee, strippers following said rollers to remove the printed material from said form 85 and type holder, means for positioning an envelop over the type in said holder in printing position on said block and means for lifting said envelop after the printing thereof into engagement with said strippers. 100

9. In a printing machine, three coöperating elements, one a type form and the other two platen rollers adapted to travel over said form, a filling in type block placed in 105 said form, a filling in type holder adapted to be placed in printing position on said block to print the name and post office of an addressee on a letter sheet and envelop, said rollers successively coöoperating with type in said form and in said holder and with type in said holder alone, strippers following said rollers and adapted to remove printed material from said form and holder, means for lifting the envelops above said holder into position to be engaged by said strippers after printing and a guide carried by 110 said lifting means for assisting in positioning an envelop in printing position above the holder in printing position on the block. 115

10. In a printing machine, a type form, a bed frame on which said form is mounted, platen elements adapted to coöperate with type in said form to produce printing impressions, an inking ribbon disposed between said form and platen elements, a filling in type block in said form, a type holder movable upon said block into printing position in said form, said platen elements being adapted to travel orbitally into successive coöperation one with the type in 120 125 130

5 said form and holder and the other with the type in said holder, a paper stripper following each of said platen elements to remove printed material from said form, a lifter spanning said ribbon and adapted to raise printed material above said holder into position to be engaged by one of said strippers, and a longitudinal guide detachably secured to said frame and adjustable transversely to the travel of said holder to assist in positioning printing material transversely over said holder.

10 11. In a printing machine, a stationary printing form, two alternately acting platens arranged to travel over said form and print by rolling contact alternately from two portions of said form and from one portion of the same form and means for adjusting the height at which said platens travel over said form.

15 12. In a printing machine, a type form having a changeable portion, two platen elements movable longitudinally over said form and adapted to coöperate successively with type in the entire form and with type in the changeable portion only, means for adjusting said platen elements evenly in height over the type in said form and means for positioning printing material over said form 20 to register either with type in the entire form or with type in the changeable portion only.

25 13. In a printing machine, a type form, a flat bed on which said form is mounted, platen rollers adapted to coöperate with type in said form to produce printing impressions, an inking ribbon disposed between said form and platen elements, a filling in type block in said form, a type holder movable upon said block into printing position in said form, said platen elements being adapted to travel orbitally into successive co-operation one with the type in said form and holder and the other with the type in 30 said holder alone, a paper stripper following said platen elements to remove printed material from said form, a lifter spanning said ribbon and adapted to raise printed material above said holder into position to be engaged by said stripper, a guide for positioning printing material above said form secured to said lifter, means for raising said lifter into superior position after coöperation between said platen rollers and the 35 type in said form and skid rails on said bed adjustable vertically and adapted to co-act with said rollers to assist in producing an even printing impression.

40 14. In a printing machine, an immovable type form having an inserted portion, two platens arranged in series and adapted during a single stroke and while said inserted portion remains stationary in said form, to coöperate one with type in the entire form 45 including the inserted portion and the other

5 with type in the inserted portion only, means for positioning printing material over said form to register either with type in the entire form or with type in said inserted portion, an inking fabric between said type form including its inserted portion and said platens, and means for lifting said ribbon clear of the inserted portion of said form after a printing impression.

70 15. In a printing machine, an immovable type form having an inserted portion, two platens arranged in series and adapted during a single stroke and while said inserted portion remains stationary in said form, to coöperate one with type in the entire form including the inserted portion and the other with type in the inserted portion only, adjustable means for selectively positioning printing material over said form to register either with type in the entire form or with type in said inserted portion, an inking fabric between said type form including its inserted portion and said platens, and means for lifting said ribbon clear of the inserted portion of said form after a printing impression.

75 16. In a printing machine, an immovable type form having an inserted portion, two platens arranged in series and adapted during a single stroke and while said inserted portion remains stationary in said form, to coöperate one with type in the entire form including the inserted portion and the other with type in the inserted portion only, adjustable means for selectively positioning printing material over said form to register either with type in the entire form or with type in said inserted portion, an inking fabric between said type form including its inserted portion and said platens, means for lifting said ribbon clear of the inserted portion of said form after a printing impression, and means for engaging and removing said printing material from said form.

80 17. In a printing machine, an immovable type form having an inserted portion, two platens arranged in series and adapted during a single stroke and while said inserted portion remains stationary in said form, to coöperate one with type in the entire form including the inserted portion and the other with type in the inserted portion only, means for adjusting said platens in height above said form, and means for positioning printing material over said form to register either with type in the entire form or with type in said inserted portion.

85 18. In a printing machine, an immovable type form having an inserted portion, two platens arranged to coöperate one with said type form and its inserted portion simultaneously and the other with said inserted portion only, means adjustable laterally for positioning printing material over said form

to register accurately with type in the entire form and with type in said inserted portion, said platens comprising two platen rollers movable orbitally around said form, 5 and means for adjusting the height at which said rollers travel above the type in the entire form and the type in the inserted portion.

19. In a printing machine, an immovable 10 type form having a changeable portion, platen means movable over said form and adapted to coöperate successively with type in the entire form and with type in the changeable portion only, means for adjusting said platen means evenly in height over the type in said form, whereby an even printing impression is produced, and means for positioning printing material either over said form or over only said changeable 20 portion.

20. In a printing machine, an immovable form for the body of a letter associated with a removable address form, two platens, one being adapted to coöperate with the body 25 and address and the other with the address only while the latter remains in the same position with relation to the body, and means for positioning printing material in printing position to receive an impression 30 from either the body and address simultaneously or from the address only.

21. In a printing machine, a stationary printing form, two alternately acting platens arranged to travel over said form and to 35 print by rolling contact alternately from two portions of said form and from one portion of the same form, a single fabric through which both imprints are made, and means for adjusting the height at which 40 said platens travel over said form.

22. In a printing machine, a stationary printing form, two alternately acting platens arranged to travel over said form and to print by rolling contact alternately from 45 two portions of said form and from one portion of the same form, a single fabric through which both imprints are made, means for adjusting the height at which said platens travel over said form, and 50 means for positioning material either over the entire form or only a portion thereof.

23. In a printing machine, a station-

ary printing form, two alternately acting platens arranged to travel over said form and to print by rolling contact alternately 55 from two portions of said form and from one portion of the same form, a single fabric through which both imprints are made, means for adjusting the height at which said platens travel over said form, means 60 for registering printing material with either the entire form or only a portion thereof, and means for removing said material from either portion of said form.

24. In a printing machine, a stationary 65 printing form, two alternately acting platens arranged to travel over said form and to print by rolling contact alternately 70 from two portions of said form and from one portion of the same form, a single fabric through which both imprints are made, means for adjusting the height at which said platens travel over said form, means 75 for registering printing material with either the entire form or only a portion thereof, means for removing said material from either portion of said form, and means for lifting said fabric above a portion of said form.

25. In a printing machine, means for supporting a form for the body of a letter and a changeable address form in stationary position, two rotative platens, on parallel axes and adapted to travel orbitally about said forms, means whereby one of said platens 80 coöperates with both the body and address and the other with the address only, a single inking ribbon through which both the combined and single impressions are made, whereby the machine may print the equivalent of addressed letters and corresponding 85 envelopes, means for lifting the letters and envelopes above the forms after the impressions, and means for engaging the letters and envelopes while elevated and removing 90 them from the forms.

In testimony whereof, I have signed my name to this specification in the presence of two subscribing witnesses.

ERNEST DUSCHER.
